UNITED STATES PATENT OFFICE.

HAROLD J. CARMODY, OF BROOKLYN MANOR, NEW YORK, ASSIGNOR OF ONE-HALF TO
JOSEPH A. FAUROT, OF NEW YORK, N. Y.

INTERNAL-COMBUSTION ENGINE.

1,378,092.

Specification of Letters Patent. Patented May 17, 1921.

Application filed April 26, 1918. Serial No. 230,875.

To all whom it may concern:

Be it known that I, HAROLD J. CARMODY, a citizen of the United States, residing at Brooklyn Manor, in the county of Queens 5 and State of New York, have invented certain new and useful Improvements in Internal-Combustion Engines, of which the following is a full, clear, and exact description, such as will enable others skilled in the art to which it appertains to make and use the same.

This invention relates generally to internal combustion engines, and with respect to its more specific features to valves and 15 valve operating mechanisms therefor.

One of the objects of the invention is to provide an internal combustion engine of few parts and of simple construction, such as to assure quiet, smooth and efficient operation, and not easily susceptible to overheating; one that is durable, yet at the same 20 time relatively inexpensive to construct and maintain.

Another object of the invention is to provide a practical valve mechanism of comparatively few parts for internal combustion engines having one or more cylinders, the number of parts comprising the valve mechanism being substantially the same 25 whether the engine comprises a single cylinder or a plurality of cylinders.

Another object of the invention is the provision of an efficient rotary valve whereby the opening and closing of the ports between the intake and exhaust manifolds and the cylinders may be effected quickly and positively, and to insure an effective opening 35 into the cylinder for the intake and exhaust of the gases, and a quick and effective closure of the cylinder ports at the required times.

Another object of the invention is to provide, in an internal combustion engine having a rotary valve, a valve-operating mechanism whereby the operation of the valve is positively synchronized with the rotation of the crank shaft of the engine and with the stroke of the pistons in the respective cylinders, the mechanism being simple, light and 45 inexpensive in construction and easily accessible for ready adjustment or replacement of parts.

Another object is to provide a gearing particularly suitable and efficient for operat-

ing a rotary valve of a multiple cylinder 55 engine.

Other objects will be in part obvious and in part pointed out hereinafter.

The invention accordingly consists in the features of construction, combinations of 60 elements, and arrangement of parts which will be exemplified in the construction hereinafter set forth, and the scope of the application of which will be indicated in the following claims.

Referring more specifically to the drawings forming part of this specification, and wherein similar reference characters refer to similar parts throughout the several views,—

Figure 1 is a side view, partly in section, of a multiple cylinder internal combustion engine embodying the invention;

Figs. 2 and 3 are views of details of the valve-actuating mechanism;

Fig. 4 is a view of one valve member; Fig. 5 is a view of another valve member; Fig. 6 is a detail of construction;

Fig. 7 is a perspective view, partly in section, of a cylinder head incorporating applicant's valve mechanism, and a casing therefor;

Fig. 8 is a perspective view of a cylinder block;

Fig. 9 is a perspective generally diagrammatic view of a modified construction in which the rotary valves are disposed at the sides of the cylinders;

Fig. 10 is a fragmental view showing a lubricating system for the engine;

Fig. 11 is a perspective detail view of a valve carrier which may form part of the casing; and

Fig. 12 is a view of the inner rotary valve member of Fig. 9.

In the accompanying drawings the invention is shown incorporated in a four cycle, four cylinder internal combustion engine, having cylinders 1, 2, 3, and 4, respectively, pistons 5, 6, 7, and 8, respectively, piston rods 9, 10, 11, and 12, respectively, and crank shaft 13. The cylinders and the crank shaft are inclosed by a casing 14 in the usual manner, the casing being provided with passages 15 forming water jackets 100 about the cylinders for cooling purposes.

An intake port 16 and an exhaust port 17 are provided in the head of each cylinder.

These ports communicate through the valve mechanism 18 with the intake manifold 19 and with the exhaust manifold 20 of the engine, respectively, the valve mechanism 5 forming the usual function of permitting or preventing the flow of gases between the cylinders and the intake and exhaust manifolds. In Fig. 1 of the drawings the valve mechanism is shown to be surrounded by a 10 casing member 21 extending longitudinally across the tops of the cylinders, and contains ports 22 and 23, respectively, registering with ports 16 and 17 in the cylinder heads. Valve casing 21 may be secured to 15 the cylinder heads in any suitable manner, as by bolts 24 connecting shoulders 26 and 27 on casings 14 and 21, respectively.

In the present embodiment the valve mechanism comprises two concentric valve 20 members 28 and 29 rotatably mounted (see Figs. 4 and 5). Valve member 28 comprises a tube having transverse ports 30 in its side and is mounted for snug rotation in valve casing 21. Valve member 29 comprises a 25 rod or solid shaft having transverse ports 31, and is mounted for snug rotation in valve member 28. The ports in each of the valve members are so positioned that, at predetermined times, ports in one member 30 will register with ports in the other, to form passageways through the valve members for the passage of gases therethrough and permit the gases to flow between the cylinders and the intake and exhaust manifold of the 35 engine while at other times these passages are closed. The intake and exhaust manifolds 19 and 20 are connected to the casing in any suitable manner, and communication is established with ports in the valve members 40 through ports 30' in the valve casing. It is to be understood that the ports in the valve members are so placed that at predetermined times during the operation of the valve there will be direct communication 45 from each cylinder with the intake manifold of the engine, and at other predetermined times with the exhaust manifold of the engine, and that at certain times the passageway will become closed and remain 50 closed for a predetermined time.

In the present embodiment, the operation of the valve and the opening and closing of the desired ports of the cylinders is effected and synchronized with the revolution of 55 the crank shaft and with the position of the pistons in the cylinders of the engine by means of a spiral wheel comprising a thread 32 carried on disk 33, which disk is securely mounted on crank shaft 13 and rotatable therewith. This thread enmeshes a 60 spur gear or toothed wheel 34, which is rotated by the thread as the disk rotates with the crank shaft. The movement of the spur gear is caused to be variable by providing a 65 distorted thread on the disk. This toothed

wheel is securely fastened to a shaft 35 on which is mounted a bevel gear 36. Valve member 28 is provided with a bevel gear 37, and valve member 29 is provided with beveled gear 38, which gears mesh with gear 36 70 on opposite sides, so that when gear 36 is rotated, gears 37 and 38, and the respective valve members rotate in reverse directions. If desired this valve actuating mechanism may be inclosed in a suitable casing, which 75 may comprise casing member 39 secured to cylinder casing 14 and to valve casing 21 by a series of bolts and nuts, as illustrated in the drawings at 40, and may be utilized to provide a bearing for shaft 35. Casing 39 80 may also be provided with flange 42 bearing against the end of valve member 29 to hold it securely against longitudinal movement in its bearing, and valve member 28 may be supplied with a collar 43 adapted to bear 85 against valve casing 21 to hold this valve member against longitudinal movement.

It is to be understood that the movements of the valve members relative to that of the crank shaft are governed by the shape of the 90 thread 32 on the spiral wheel, the number of teeth on wheel 34, and the relative sizes of beveled gear wheels 36, 37 and 38. In the embodiment here illustrated, the crank shaft makes four turns to each revolution of 95 either valve member. This gives a four cycle action.

By the reverse movement of the valve members a quick opening and closing of the ports is obtained, and it is thereby permitted 100 to make the ports somewhat large compared to the size of the cylinder and thereby insure the easy flow of the gases into and from the cylinders.

Figs. 7 and 8 illustrate the rotary valve 105 device associated as a component part of a removable cylinder head, and offers a practical and efficient means for modifying many multi-cylinder engines of standard construction so as to incorporate rotary valve mechanism therewith instead of the customary 110 puppet valves, etc., the modified engine thus acquiring all the advantages of an engine fitted with the rotary or sleeve valve.

In the illustration the cylinder block of 115 the engine is illustrated at 50 and comprises cylinders 51, with water jackets 52, having passages 53 generally similar to the other illustrated form. The numeral 54 indicates the usual water inlet pipe connecting the radiator with the water jackets about the cylinders, and 55 indicates holes in the cylinder block adapted to receive stud bolts used to bolt the cylinder head in place upon the cylinder block. The cylinder head is 120 indicated at 56, and comprises the water jacket construction, having water passages 57 adapted to register with passages 53 in the cylinder block. The head is supplied 125 with the usual pipe 59 whereby the water 130

jacket is connected to the radiator for cooling purposes. The head contains perforations 58 adapted to coöperate with holes 55 in the cylinder block to permit the bolting 5 of the head to the cylinder block. A portion of this head is shaped to form a water-jacket casing for applicant's rotary valve members. The casing is indicated at 60 having water jacket 61 communicating with the 10 water jacket in the head over the cylinders. The valve members are indicated at 28 and 29, respectively, carrying the gears 37 and 38, respectively, as before described, which gears may also be incased, if desired. Between 15 the portion of the head over the cylinders and the valve members are supplied the inlet and exhaust ports indicated at 16 and 17, the valve members operating in the manner previously described. This head and 20 valve casing may be cast in a single piece and, as stated, is easily fitted to the cylinder block of many engines of standard construction. Or the engine may of course be constructed originally with the removable 25 type of head and associated valve.

Instead of arranging the rotary valve members as heretofore specifically described, they may be supported in a tubular valve carrier 62 comprising an elongated box, the 30 inner surface of which provides a journal in which the outer rotary valve member 28 of the pair of concentric rotatable valve members bears, the inner rotary valve member 63 being in the present instance preferably hollow or tubular, as illustrated in Fig. 12, one end, 64, being closed, and the opposite end provided with a port 65 substantially on the axis of the member for the introduction of lubricating oil. The carrier 62 is 35 provided with inlet and exhaust ports or passageways 66 and 67, and the inner valve member is also provided with inlet and exhaust ports or passageways 68 and 69, respectively, comprising, in the present instance, transversely disposed pipes to seal these ports from communication with the interior of the tubular member. The numerals 70 and 71 indicate oil ports in the 40 outer member communicating with the interior thereof, and being adapted to convey oil to between the valve members, and also being adapted to register with the ports 71 in the outer member to convey lubricating oil to 45 the bearing of the outer valve member. The end of the casing 39, as illustrated at the right hand end of Fig. 1, may be utilized as a continuation or extension of the valve carrier 62 so that the transmission gearing 50 serving to rotate the valve members on the crank shaft 13 may be completely housed and enabled to run in the lubricating oil. The numeral 72 indicates a centrifugal oil pump, the piston of which is operated by 55 the crank shaft, the operation of the pump

serving to conduct lubricating oil to the casing for the purpose of supplying the transmission gearing and the rotary valve members. Pin-hole ports may be provided at various places, as for instance, at 73 and 74 for the more free flow of the lubricating oil. It will be observed that the port 65 in the inner valve member is disposed at such a point that the inner valve member becomes a receptacle below the level of this port so that, in the event that the supply of lubricating oil should be cut off, sufficient oil will be retained in the member 63 to lubricate the adjacent parts, the port 65, as arranged, serving to maintain a predetermined level of oil in the inner valve member.

The valve carrier 62 is provided with flanges 75 having bolt openings 76 for the convenient fastening of the carrier alongside the several engine cylinders in proper position so that the inlet and exhaust ports 66 and 67 shall register with the similar ports in the several cylinders. In this wise many forms of engine having valve operating mechanism of a widely different character from that herein disclosed may be supplied with the herein disclosed valves and valve operating mechanism, it being merely required to remove the usual valves and fasten the valve carrier 62 in position alongside the cylinders. Thereupon the inlet and exhaust manifolds 76 and 77 which may have been removed or bent aside may be fastened to the outer face of the carrier 62.

It will be noted that the valve members 28 and 29 are disposed concentrically to each other and rotate in opposite directions; also that each engine cylinder has two ports 22, 23, which are in different planes crossing the axis of rotation of the valve members.

It will be further noted that in the same planes as the engine ports 22, 23 are the valve ports 30, 31, so arranged that at one instant a port 30 of the valve member 28 and a port 31 of the valve member 29 are brought into registry with each other and with an engine port 22, and at another instant another port 30 and another port 31 are brought into registry with each other and with an engine port 23.

This action enables one of the engine ports of each cylinder to serve as an intake port, and the other of the engine ports to serve as an exhaust port.

By this arrangement of the mechanism the rotation of the valve members 28 and 29 in opposite directions brings each cylinder into condition for intake, compression, explosion and exhaust.

The staggering of the ports 30 and 31 causes the cylinders to fire in a predetermined order of succession.

The spiral cam gearing is so proportioned and arranged that the valve members 28, 29

130

though rotated positively and each at the same speed as the other, are as a unit rotated at varying speeds, dependent upon the necessity for quickly opening and quickly closing communication between the cylinders and the manifolds.

It will also be observed that although the engine has four cylinders and might have a larger number, the number of valve members 28, 29 is only two, and that each of these valve members rotates very slowly as compared with the speed of the crank shaft. Thus the valve mechanism as a whole is very simple, and the degree of movement going on within it is reduced to a minimum. Again, as each valve member 28, 29 is quite lengthy, the amount of lost motion is greatly reduced, vibration is lessened, shocks are avoided, and pounding is prevented.

10 The cylinders are not in immediate proximity to the manifolds, and the valve members 28, 29 are out of contact with the movable pistons. Not much heating and very little friction is developed.

20 By having the valve members 28, 29 comparatively long and few in number, the strains upon the connecting rods are kept down about as low as possible, and the strains upon the bearings are accordingly 30 reduced.

The practical advantage in the form and arrangement of the parts whereby a puppet valve engine can be readily and cheaply converted into an engine of the general type 35 here contemplated is considerable.

Although many advantages and efficiencies result from the association of rotary valve members, as described, with the form of gearing herein disclosed for transmitting 40 motion thereto from the crank shaft, it will be understood that viewed in some aspects the invention is not to be regarded as limited to the special type of transmission mechanism disclosed, but that other forms might 45 be employed, as for instance, elliptical gearing or scroll gearing.

Thus by the above described construction are accomplished, among others, the objects hereinbefore referred to.

50 As many changes could be made in the above construction, and many apparently widely different embodiments of this invention could be made without departing from the scope thereof, it is intended that all matter contained in the above description or 55 shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might 65 be said to fall therebetween.

Having described my invention, what I claim as new and desire to secure by Letters Patent is:—

1. In a device of the character described the combination of a pair of valve members disposed concentrically to each other and revoluble upon a common axis, said valve members each being provided with transversely disposed ports located in different planes crossing said axis, some ports of each valve being staggered so as to cross other ports of the same valve, and a plurality of engine cylinders each provided with an inlet port located in one of said planes and with an exhaust port located in another of said planes, the arrangement being such that by the rotation of said valve members first a pair of transverse ports in one plane are brought into registry with an inlet port of the engine, and then a different pair of transverse ports in another plane of the same valve, crossing the ports thus brought into registry with the inlet port of the engine are brought into registry with an exhaust port of the engine. 90

2. In a device of the character described the combination of a pair of valve members disposed concentrically to each other and revoluble upon a common axis, said valve members each being provided with transversely disposed ports located in planes crossing said axis, one of said transversely disposed ports crossing another transversely disposed port of the same valve member and an engine cylinder provided with an inlet port located in one of said planes and with an exhaust port located in another of said planes, the arrangement being such that by the rotation of said valve members first a pair of transverse ports in one plane are brought into registry with an inlet port of the engine, and then a different pair of transverse ports in another plane are brought into registry with an exhaust port of the engine. 100

3. In a device of the character described the combination of a pair of valve members disposed concentrically to each other and revoluble upon a common axis, said valve members each being of considerable length and provided with a number of transverse ports distributed along its length and crossing each other, said transverse ports being disposed in planes crossing said axis, and a plurality of engine cylinders each provided with an inlet port located in one of said planes and with an exhaust port located in another of said planes, the arrangement being such that by the rotation of said valve members first a pair of transverse ports in one plane are brought into registry with an inlet port of the engine, then a different pair of transverse ports in a different plane are brought into registry with an exhaust port of the same engine, the transverse ports be- 125 130 135

ing so staggered that at a particular moment the cycle in one cylinder is different from the cycle of another cylinder.

4. In an apparatus of the character described, the combination of a pair of rotary valve members fitted concentrically to each other and revoluble in opposite directions, one of said valve members comprising a solid shaft having ports extending diametrically through it and so arranged that one of said ports crosses another of said ports, means for actuating said valve members, and a valve casing provided with inlet and exhaust ports, disposed adjacent the path of travel of the ports of said valve member having the form of a solid shaft.

5. In an apparatus of the character described, in combination, a tubular valve member having transverse ports, a solid valve member having transverse ports, one of the ports of said solid valve member crossing another port thereof, said valve

member being revolubly mounted within said tubular valve member; and means for turning said valve members continuously but at varying rates of speed.

6. In an apparatus of the character described, the combination of a plurality of cylinders, a water jacketed casing therefor, a pair of rotary valves supported by said casing, one of said valves having a tubular form and the other the form of a solid cylinder, both of said valves having ports to be brought into and out of registry with ports of the valve casing, and gearing connected with said valves for the purpose of turning the same continuously but at varying speeds.

In testimony whereof I affix my signature, in the presence of two witnesses.

HAROLD J. CARMODY.
